UNITED STATES PATENT OFFICE.

CHARLES A. JUENGST, OF CROTON FALLS, NEW YORK.

METHOD OF SEWING SIGNATURES TO FORM BOOKS.

No. 893,512.

Specification of Letters Patent.

Patented July 14, 1902.

Application filed February 24, 1902. Serial No. 417,299.

To all whom it may concern:

Be it known that I, CHARLES A. JUENGST, a citizen of the United States, residing at Croton Falls, in the county of Westchester and State of New York, have invented an improvement in the Methods of Sewing Signatures to Form Books, of which the following is a specification.

My invention relates to a new and novel manner of sewing the signatures of books so that they are held firmly together, with the object of providing for a book when open lying as flat as possible to facilitate the use thereof.

15 In carrying out my invention, I lay a thread along through and within the back fold of each of the several signatures composing the book in succession, that is to say, each thread extends completely through the 20 fold of the signature from one end to the other, and the ends preferably project slightly. Suitable devices are employed within the fold of each signature for pushing out through the back fold of the signature 25 several loops of this thread and these loops are in alignment across the back of the collated signatures and the loops of each signature are successively inter-looped with the loops of thread of the preceding signature, 30 thus similarly positioned loops are inter-looped over the backs of the signatures. These loops are also successively drawn down taut so as to consolidate the sewing and bind the signatures tightly together. The loops of 35 the last signature are not drawn down as tight as the preceding loops and are only drawn snugly into position; the glue employed upon the backs of the signatures and particularly over the threads when dry holding the 40 threads in position so that they cannot shift.

In the drawing, Figure 1 is a perspective view of a series of signatures representing the form of sewing the signatures together according to the method of my invention. 45 Fig. 2 is a partial cross section at the dotted line *x*, *x*, of Fig. 1. Fig. 3 is a broken inverted plan of one of the signatures laid out flat showing a thread and perforations in the back fold through which the loops of this 50 thread are passed, and Fig. 4 is a perspective view of a fragment of the inter-looped threads alone.

55 Referring particularly to Fig. 1, *a b c d e f g* and *h* represent the signatures of a series brought together side by side and sewed.

2 3 4 5 6 7 8 and 9 represent threads which are passed along through and within the back fold of each of the several signatures in succession and each thread is at several places pushed through the back fold of the signature in which it is laid at the places marked 10 and the part pushed through is left outside the back fold as a loop, and while in each of the signatures shown in the drawing there are four of these places 10, the number 65 thereof is immaterial; the same being a question of judgment of the manufacturer according to the size and weight of the signatures that are to be sewed together.

60 The devices for drawing the threads along 70 through and within the back fold of each signature and the devices for pushing the loops of thread out through the back fold form no part whatever of my present invention; they may be any devices capable of performing 75 these functions. I prefer to lay these threads along through the back fold of each signature in succession and also in succession to push parts of these threads out through the back 80 folds and leave them as loops. These loops as pushed out of the back fold of the several 85 signatures in succession are to be in alignment and in the method of introducing these threads and forming these loops, the loops of 90 each signature after the first as formed are pushed through the loops of the preceding 95 signature, so that the aligned loops are inter-looped over the backs of the respective signatures as illustrated in the drawing, and the 100 threads are then drawn upon at one or both ends of the signatures so as to draw down the loop as much as possible in tightening the threads and in connecting the signatures together as sewed. Suitable devices are of course employed for inter-looping these 105 loops and for drawing down these threads, but these devices like the devices for laying threads through the signatures and forcing 110 said threads and loops out of the folded back form no part of my invention. They may be well known devices or some particular devices to be hereafter arranged for. The loops of the last of these collated signatures are to be drawn in to the desired extent, the previously formed loops of course being drawn tight around the same and when glue is applied to the backs of the signatures and particularly to the lines of inter-looped loops, the same are upon the drying of the glue held firmly and substantially inseparable in their 115

relation in such form that the cover is readily applied in any well known manner in the practice of this art.

Fig. 2 illustrates clearly the inter-looping 5 of the loops. Fig. 3 illustrates clearly the single thread with parts thereof through the openings made by the pushing device in the folded back of the signatures and Fig. 4 clearly shows by the perspective view the 10 threads with their loops separate from the signatures; this method of sewing signatures to form books having particular reference to the cheaper form of books or those inexpensively made.

15 I claim as my invention:

1. The method herein specified of sewing signatures to form books, consisting in laying successive threads along, through and within the back fold of the several signatures forming 20 a book, successively pushing several loops of each thread out through the back fold of each signature and successively inter-looping the loops of each signature with the alining loops of the preceding signature.

25 2. The method herein specified of sewing signatures to form books, consisting in laying successive threads along, through and within the back fold of the several signatures forming a book, successively pushing several

loops of each thread out through the back 30 fold of each signature in alinement and successively inter-looping the loops of each signature with the loops of the preceding signature so that similarly positioned loops are interlooped in line over the backs of the 35 signatures.

3. The method herein specified of sewing signatures to form books, consisting in laying successive threads along, through and within the back fold of the several signatures forming 40 a book, successively pushing several loops of each thread out through the back fold of each signature in alinement and successively inter-looping the loops of each signature with the loops of the preceding signature 45 so that similarly positioned loops are interlooped in line over the backs of the signatures, the loops of the last sewed signature being drawn down appreciably and glue applied to the loops in line to complete the 50 hold and firmly hold the loops together.

Signed by me this 28th day of January 1908.

CHAS. A. JUENGST.
